(57) **CLAIM**

The ornamental design for a privacy screen for a self-service terminal, as shown and described.

DESCRIPTION

FIG. 1 is a left front perspective view of a privacy screen for a self-service terminal, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a right front perspective view of one portion of a privacy screen for a self-service terminal shown separately for purposes of illustration; and,

FIG. 8 is a right front perspective view of one portion of a privacy screen for a self-service terminal shown separately for purposes of illustration.

The broken lines are for illustrative purposes only and forms no part of the claimed design.
